ELECTRON DISCHARGE DEVICE AND
ITS CIRCUITS

Louis W. Parker, Jackson Heights, N. Y., assignor
to Federal Telephone and Radio Corporation,
New York, N. Y., a corporation of Delaware

Application December 8, 1945, Serial No. 633,804

3 Claims. (Cl. 315—42)

1

This invention relates to electron-discharge devices and their circuits, and particularly to high frequency wide-band amplifiers employing such devices.

In the operation of amplifiers at the higher frequencies, the inter-electrode capacities of the electron discharge devices employed therein become an important factor tending to lower the input and output impedances and consequently lowering the gain of such amplifiers. The frequencies at which these effects occur vary with the particular tube and circuit arrangement, but the lowering of efficiency of such amplifiers, due to these inter-electrode capacities, is usually quite pronounced in the range above one megacycle.

An object of the present invention is the provision of an improved electron-discharge device and particularly one adapted for distributed amplification for use at the higher frequencies.

Another object of the present invention is the provision of an improved electron-discharge device in which the deleterious effects of the inter-electrode capacities are diminished without substantially changing the overall area of the electrodes.

Another object is the provision of an improved amplifying device adapted for use at higher frequencies and characterized by greater gain.

Other and further objects of the present invention will become apparent and the invention will be best understood from the following description of an embodiment thereof, reference being had to the drawings, in which:

Fig. 1 is a schematic diagram of a conventional two-stage amplifier;

Fig. 2 is an equivalent circuit of the changes made in said amplifier in accordance with one aspect of my invention;

Fig. 3 is a schematic diagram of a two-stage amplifier embodying my invention;

Fig. 4 is a diagrammatic plan view of a tube constructed in accordance with my invention; and

Fig. 5 is a broken-away detail, taken in side elevation, of a portion of the tube illustrated in Fig. 4.

In conventional amplifiers, the inter-electrode capacities of the tubes employed therein limit the gain, the effect of said capacities being greater the higher the frequency at which the amplifier is operated. For example, in the conventional amplifier illustrated in Fig. 1, which includes two tubes 1 and 2 coupled together by a condenser 3, the output capacity of tube 1, designated by the numeral 4, consisting of the capacity between the

2

anode and cathode is substantially in shunt across the output thereof. There is also an input capacity 5 in shunt across the input of tube 2, that is, between the grid and cathode of tube 2. These two capacities 4 and 5 cause a substantial decrease in the gain of the amplifier.

In accordance with one aspect of this invention, the gain of such amplifiers is increased by splitting the input and output capacities of the amplifier tubes in small parts and inserting small inductances between the split parts. Fig. 2 represents the equivalent circuit of what is thereby accomplished. It will be seen from Fig. 2 that what is produced by the foregoing is equivalent to a low-pass filter circuit. As in low-pass filters the load impedance increases as the individual capacities are lowered. Consequently, by splitting up the input and output capacities in the amplifier tubes and inserting inductances therebetween, a higher load impedance is produced, thus resulting in greater gain for the amplifier.

Referring now to Fig. 3, in which two stages of an amplifier are illustrated, there are two tubes 6 and 7; 6 being the first tube and 7 the second tube. Each of said tubes includes a cathode, grid and anode, but unlike standard grids and anodes, the grids of tubes 6 and 7 are split into a plurality of separate sections 8 which are connected together by series lumped inductance coils 9. Similarly the anodes are split into a plurality of separate plates or sections 10 which are connected together by series lumped inductance coils 11. In the embodiment illustrated, the anode of tube 6 is separated into two plates, whereas the anode of tube 7 is separated in the three plates. It will be of course appreciated that many more plates may be employed and that the number of plates and tubes of the separate stages do not necessarily have to be of the same amount. This also holds for the number of sections into which the grids are split. It will be recognized that tubes 6 and 7 are coupled together by the equivalent of the low-pass filter circuit shown in Fig. 2, in which the capacities are relatively small due to the break-up of the anodes and grids into small portions forming small inter-electrode capacities with the other elements of the tubes.

The insertion of inductances in the electrodes together with the inter-electrode capacity, introduce a small but possibly appreciable time delay during the travel of energy from one end of an electrode to its other end, since substantial values of L and C are involved and time delay is proportional to $\sqrt{LC}$. In order to compensate

for this time delay, the input 12 to tube 6 is applied through a lead 13 to one end (the lower end) 14 of the grid. The signal energy is taken from the anode 6 at the end 15 thereof, opposite the end 16, which is adjacent to end 14 of the grid. In tube 7 the signal energy is applied to end 17 of the grid and is taken off the anode at opposite end 18 thereof. It will be seen that the anodes are provided with two leads through the envelope, the signal energy being taken off at one end of the anode with the plate resistor 19 and the positive side of a source of anode potential 20 applied at the other end thereof. Two leads may also be provided for the grids, for example, for the purpose of connection of the grid leak 21 and a source of biasing voltage 22.

In conventional type tubes, the inter-electrode capacity is not split up. Furthermore the inductance inherent in the electrodes is so small as to be practically of no effect. Anodes are usually made in the form of solid plates whose inductive reactance is extremely small. While the turns of the grid wires would tend to have some appreciable inductance, the supporting rods on which the grid wire is wound and to which the grid wire is welded, serves to reduce this inductance to an insubstantial amount by shorting these turns.

In contrast, a tube embodying my invention is illustrated in Figs. 4 and 5. This tube 23, has an envelope 24, within which is mounted a cathode 25, of the indirectly heated type and whose exterior is substantially rectangular in cross section. The cathode is surrounded by a grid 26 also rectangular in cross section. On opposite sides of the wide faces of the grid 26 are arranged the halves of the screen grid and suppressor grid 27 and 28 respectively, the opposite halves of which are connected together by wires 29 and 30 respectively. The anode 31 is also comprised of two halves 32 and 33 respectively which are connected together by wires or leads 34.

Both the grid 26 and the anode 31 are split up into small portions or sections which are connected together by lumped constant inductance coils. For example (see Fig. 5) each half of the grid 26 consists of a plurality of sections arranged vertically one above the other and insulated from each other. Each section of the grid is welded to a U-shaped member 35, which is mounted on an insulating support 36, consisting of a plurality of beads 37, held together by a wire 38. A plurality of lumped constant inductance coils 39 are each connected in series between a separate pair of adjacent U-shaped conductors 35. The inductances 39 are staggered and arranged on opposite ends of the grid structure so as to occupy the minimum of space and be separated as much as possible from each other. Likewise each half of the anode 31 is vertically divided into a plurality of separate plates or sections 40, adjacent pairs of which are connected together in series with one of a plurality of lumped constant inductance coils 41. Each of the anode halves may consist of two or more plates depending upon the specific conditions encountered. The inductance coils 41 are arranged toward the middle of each half of the anode 31. To prevent interaction between the inductance coils 39 and 41, and to provide some measure of inter-electrode shielding, a plurality of shields 42 is arranged at the ends of the anodes and extend between the

suppressor and screen grids and the coils 39. The values of inductance coils 39 and 41 are such as to provide a substantial inductive reactance at the operating frequencies of said electron discharge device.

In certain instances the leads to the electrodes in the tubes, and the socket prongs for the tubes may have a substantial capacity. To include this capacity as part of the low pass filter, inductances 10 would have to be arranged on both sides of this capacity. Therefore if such capacity exists and as in Fig. 3, inductances are arranged within the tubes, where one or more additional inductances will have to be arranged outside the tubes, as for example, inductances 43 and 44.

It will of course be understood that while I have described the specific details of an embodiment of my invention, numerous changes may be made therein, as will be apparent to those versed in the art. Accordingly, while I have described above the principles of my invention in connection with specific apparatus, it is to be clearly understood that this description is made only by way of example and not as a limitation on the scope of my invention as defined in the accompanying claims.

I claim:

1. An electron discharge device comprising an envelope, a cathode, grid and anode mounted within said envelope, said grid and anode each having portions between which there is a substantial inductance, thereby introducing a progressive time delay between one end of said grid and an opposite end thereof, and a progressive time delay between one end of said anode and the opposite end thereof, a lead to a given end of said grid extending through the envelope and a lead to an end of said anode opposite the end thereof adjacent said given end of the grid.
2. An electron discharge device according to claim 1 further including a second lead to said anode to the end thereof adjacent said given end of the grid, said second lead extending through the envelope.
3. An electron discharge device comprising an envelope, a cathode, grid and anode mounted within said envelope, said grid and anode each comprising a plurality of sections, lumped inductance means connecting the anode sections in series and having a value of inductance providing a progressive phase shift between opposite ends of said anode, lumped inductance means connecting the grid sections in series and having a value of inductance providing a progressive phase shift between opposite ends of said grid, input means connected to a given end of said grid for impressing a signal on said given end of the grid, and output means connected to an end of said anode opposite the end thereof adjacent said given end of the grid.
